John M. Black, Chicago, Ill., assignor to Superior Plastics Inc., Chicago, Ill., a corporation of Illinois

Application February 2, 1952, Serial No. 18,348

Term of patent 14 years

(Cl. D44—29)

To all whom it may concern:

Be it known, that I, John M. Black, a citizen of the United States, residing at Chicago, in the county of Cook and State of Illinois, have invented a new, original, and ornamental Design for a Wall Plaque or Similar Article, of which the following is a specification, reference being had to the accompanying drawing, forming part thereof.

Fig. 1 is a front elevational view of a wall plaque showing my new design;

Fig. 2 is a top plan view thereof;

Fig. 3 is a bottom plan view thereof;

Fig. 4 is a rear view thereof; and

Fig. 5 is an end elevation.

I claim:

The ornamental design for a wall plaque or similar article, substantially as shown.

JOHN M. BLACK.
